UNITED STATES PATENT OFFICE.

DAVID H. DARRIN, OF NEW YORK, N. Y.

MAGNET-ACTUATED DEVICE.

,015,787.

Specification of Letters Patent. Patented Jan. 30, 1912.

Application filed November 14, 1906. Serial No. 343,343.

To all whom it may concern:

Be it known that I, DAVID H. DARRIN, a citizen of the United States, residing at New York city, in the county of New York and State of New York, have invented certain new and useful Improvements in Magnet-Actuated Devices, of which the following is a full, clear, and exact specification.

This invention relates to magnet actuated mechanism, and has especial reference to apparatus wherein a switch, a rheostat, a valve, a brake, or the like is actuated by a magnet.

The object of the invention is to provide an apparatus in which the movement of a part actuated by the current automatically deenergizes the magnet, so that after the part is started, the magnet is automatically cut out, thereby preventing waste of current or overheating in the magnet, but always leaving the magnet in condition to be again energized for the succeeding actuation of the part, plunger, switch, valve, brake, or whatever device it is desired to operate.

More particularly described, the invention comprises a mechanism having two positions, and so connected with the magnet armature or core that the initial pull of the magnet sets the mechanism in motion, the magnet circuit being thereafter opened, and the further movement of the apparatus effected by the momentum of the parts, or by other means, the magnet circuit being automatically set at the end of the movement so that it can be energized to again operate the apparatus in the reverse direction.

A characteristic feature of the invention is that none of the energy of moving parts is used up in resetting the mechanism for the next action, this being done by the force of gravity which causes the parts to fall to a position where the next energization of the magnet will lift them.

In one application of the invention, the movement of the actuated part is greater in one direction than in the other. This arrangement has especial advantages for certain purposes, and is shown herein applied to a motor starter or rheostat.

Further objects of the invention are improvements in the operation and arrangement of electric switches and in the particular form and construction of the various parts, all of which will be more fully ex-

plained in connection with the accompanying drawings, wherein—

Figure 1 is a front elevation, showing the invention applied to an electric switch; Fig. 2 is an elevation showing the invention applied to a motor starter; Fig. 3 is a diagrammatic view showing a relay control; and Fig. 4 is a diagrammatic view showing the connections for a power circuit.

1 represents a base having mounted thereon a solenoid magnet 2 comprising a winding 3, and vertically movable armature or core 4.

5 is a stud mounted on a bar 6 through which latter the winding 3 of the magnet is connected with the controlling circuits. Pivotally mounted on stud 5 is an oscillating weighted crank 7, and loosely attached thereto by a slot and pin connection 8, 9, is a link 10, the upper end of which is connected with core 4 by pin 11. This provides a lost motion connection, whereby the initial magnetic pull acts to set the core and the link in motion, and the crank does not move until these parts have acquired considerable momentum. The result is, that the crank, when once started, moves quickly, with sufficient force to operate the device to be controlled, in passing from one side of the center to the other, and at the same time cutting off the magnet current after the starting impulse has occurred. Without the lost motion between the core and the actuating crank, there would be a tendency to a slow action, because the initial pull would have to move the entire mass of core and crank, but by starting the core first, and then causing it to pick up the weight

when once in motion, a much less pull will suffice to operate the device, thereby effecting a considerable economy in the current consumed by the magnet. The actuating circuits of the magnet lead from terminals 14, 15, to brushes 16, 17, with one of which the crank 7 is always in contact when at rest, so that the magnet circuit is thus set to be energized to throw the crank to the other side. From the winding 3 a wire 18 leads to a terminal 19, which will be connected with the opposite side of the line

from the terminals 14, 15, thus forming the magnet circuit, which may or may not be supplied from the same line to which the switch, rheostat or other electrical device being operated, is connected.

The construction thus far described is capable of being used in a large variety of relations as an actuating mechanism, such as for electric controlling devices, switches, 5 rheostats, brakes, valves, etc., and I will describe herein two such applications to electrical apparatus, one for a power switch and the other for a rheostat.

Fig. 1, shows a controlling switch comprising terminals 22, 23, 24, 19, resilient switch blades 25, 26, mounted on blocks 27 (connected respectively with terminals 23, 24). From the terminals 22, 19, wires 28 lead to clips 29 carrying removable carbon 15 blocks 30, which contact with removable blocks 31 carried by the switch blades 25, 26. In order to operate the switch blades, an oscillator 33, carrying insulating rollers 34 bearing on the blades, is pivoted on stud 5. 20 36 is a stop lug carried on bar 6 for limiting the throw of the oscillator. In the position shown, the switch blades are closed and the crank is on the left hand side with the upper side of the oscillator 33 positively stopped 25 against the lower end of stop lug 36, and a lug 37 on the rear side of the weight resting on the upper left side of the oscillator. When the crank throws over to the right hand side, it strikes in falling, a lug 38 on 30 the oscillator and rocks it downward on the right, moving the rollers away from the switch blades and permitting them to open, the oscillator striking the inclined side of lug 36. At each actuation, the crank runs 35 off from one or the other of brushes 16, 17, opening the magnet circuit, and then sets the magnet circuit at the other brush, for the next movement. It will thus be seen that successive actuations of the magnet 40 throw the switch, or whatever device is being operated, in opposite directions, without reversing the current, and that the actual operation of the part is accomplished by the momentum of the crank, which, after having 45 acquired sufficient momentum from the magnet to throw over, automatically cuts off the magnet current. Furthermore, it will be noticed that the crank falls until stopped positively by the oscillator in operating the 50 switch. Also the magnet core or armature correspondingly varies in its position of rest, according to which side of center the crank is on and the amount of fall permitted the crank.

55 In Fig. 2, the device is applied to a motor starter, and has a somewhat different arrangement of magnet circuit contacts. Attached to the crank 7 by a link 40 is a lever 41, corresponding to the oscillator 33, pivoted at 42 and having its short arm 43 formed with a channel in which rests the weighted end 45 of a bell crank lever, also pivoted on stud 42. The other end 46 carries a contact block 47 which moves over a set of resistance plates 48, which will be con-

nected in a motor circuit in a well known manner. Attached by rod 50 to the weight on arm 45 is a plunger 51 in dash-pot 52, the plunger having valves opening downward so that its descent will be retarded but its ascent not retarded. With the position shown in the drawing (Fig. 2) the core 4 is in its lowest position, and the magnet circuit is set at brush 16. In order to operate the rheostat, the magnet circuit will be energized (as by a switch 56, push button or the like) through brush 16, thereby drawing up the core 4 and, through link 10, throwing crank 7 to the right and opening the magnet circuit as before described. At the same time the lever 41 is moved upward by link 40, thereby moving the short end 43 from under weighted arm 45 of the rheostat lever, and allowing the weighted plunger 51 to move slowly downward in the dash-pot and move contact block 47 over the resistances. The resistance arm holds at each end according to the position of the crank and the latter is stopped positively by lugs 54, or in some other suitable manner. By raising one of lugs 54 the resistance arm 46 will be held in the left hand position, Fig. 2. In this position (dotted lines, Fig. 2), the crank 7 will have dropped a little below its highest point to prevent accidental falling back, and the core likewise have dropped somewhat, and set the magnet circuit at brush 17, so that the magnet can again be energized, to throw the crank over and permit the core to drop to its original position. By reason of the slotted link, the core falls farther than the crank. At the next actuation crank 7 and lever 41 will raise the dash-pot plunger and resistance weight and return the resistance arm to original position. With the crank 7 stopped a little below the center, it will take a very slight impulse to throw it back, but by reason of the slotted link, the core will drop to such an extent as to enable it to acquire enough momentum to accomplish this before the current through the magnet is cut off.

It will be obvious that the main motor switch may be opened and closed at the same time, as shown in Fig. 1, this being omitted from Fig. 2 for clearness, forming a complete motor controller. Ordinarily, the resistance arm when at the right will have the resistance all in, cutting it slowly out in moving to the left, but it will be seen that it could as well be all out and slowly inserted as the arm moves to the left, this depending upon the particular use to which the rheostat is to be put. By a similar mechanism a brake can be held off, or applied by momentarily energizing the magnet. Also other mechanisms may be similarly controlled, wherein it is desired to hold a part positively without requiring any current in retaining magnets.

The magnet circuit may be controlled from a distance by a relay actuating device, the relay magnet, as 57, Fig. 3, requiring a very small current. In this arrangement, a 5 hand switch 58 opens or closes the relay circuit, permitting the armature 59 to drop or rise and complete the main magnet circuit through one or the other of brushes 16 or 17. Instead of being in the relay circuit, 10 the switch 58 may be a three point switch 56 as in Fig. 4, which shows the circuits where motors or lights are to be controlled. Such a relay arrangement will be of great 15 advantage when it is desired to use this mechanism in the same manner as the usual form of solenoid or magnet switches are used; that is, where it is desired to operate a main switch by a simple breaking of the 20 relay circuit, as in connection with the various safety devices of an electric elevator. Of course, if the opposite effect be desired, that is, when the magnet coil be energized and it be desired to open the main switch instead of closing it, the same result 25 could be obtained through the relay arrangement.

An apparatus constructed as thus described, may be connected up in a number of ways and used for a variety of purposes, 30 the magnet in all cases breaking its own circuit irrespective of the circuit controlling switch as soon as contacts 16 or 17 separate from the crank, the further actuating movement of the crank being due to the momentum of the moving parts, and not requiring any current, after the initial impulse, either to cause a complete throw or to hold the actuated part in one or the other position. Furthermore, none of the energy 35 of the moving parts will be required to reset the mechanism as this automatically occurs when the parts have fallen by gravity to their respective positions of rest, ready to be lifted by the energization of the magnet 40 to accomplish another action. Also it will be seen that the apparatus will not hang on the center, leaving the mechanism partially thrown, since if the impulse is not sufficient to throw the crank entirely over, it will fall 45 back and, by closing the magnet contacts 50 again, cause another throw.

By the use of this device, the necessity for using retaining magnets for holding the actuated parts in one or another position 55 will be obviated, and thereby a large saving in current consumption obtained. When used as a motor starting switch to operate a rheostat, brake or the like, there will also be a saving of current, because it will not be necessary to keep current in the magnet 60 while the rheostat is moving, or the brake on or off, or the motor running.

Inasmuch as there is only a momentary current through the magnet, it can take 65 very large currents without damage by

overheating, and the larger the current, the stronger will be the throw of the crank, with consequent quicker cutting out of the magnet circuit. This also permits the same magnet to be used on circuits subject to 70 large fluctuations in current and voltage without being burned out, with either direct or alternating current.

For use in an alternating current circuit, this device has a number of advantages by 75 reason of the automatic breaking of the magnet circuit before the cycle of operation of the apparatus is completed. In all alternating current magnets, there is, by reason of self-induction, and the eddy currents induced in the core, a liability of overheating and damage. Furthermore, as the magnetic reluctance decreases with the inward movement of the core, the heating effect increases by reason of increase of self 80 induction, and it is therefore of advantage to prevent this heating effect by reducing the time during which the current flows as much as possible. Also, in devices to be actuated by alternating current it has been 85 necessary, in order to secure a steady pull and to prevent chattering, to use a plurality of windings, displaced in phase, but with this device, such an arrangement is not necessary, since the current is only used to 90 produce the initial impulse, and thereafter the further operation is entirely independent of the current or time.

In many cases where live retaining magnets are at present used to control a circuit, 100 this invention can be used without involving waste of current in the magnet while the circuit is on or off, and with the further advantage that the magnet, being out of circuit, will be protected against burning out 105 or overloads. With the controlling relay, as in Fig. 3, it is possible to control the actuated device by opening and closing a single circuit, and the amount of current used by the relay will be negligible in comparison 110 with that used by the actuating magnet itself, or a holding coil to hold the core elevated, as when used in a motor starter. Furthermore, the switch herein described, 115 by reason of the large movement of the switch blades, and the smaller actuating movement of the oscillator, has a number of practical advantages in quickness of action, etc., and the parts can be readily renewed or adjusted when necessary.

From the foregoing description of the invention, and the manner in which it may be applied, it will be understood that I do not restrict myself to the precise details of construction or uses as the invention may be 125 used in many other relations than those set forth. Furthermore, it is to be understood that the particular construction of solenoid herein described may be modified, 130 and various forms of magnets used.

Having thus described my invention, I declare that what I claim as new and desire to secure by Letters Patent, is,—

1. The combination with a magnet, a core 5 and an actuated part, of an intermediate momentum device connected to be actuated when the core is lifted for moving said part in both directions, said momentum device controlling contacts for interrupting the magnet circuit after it has acquired sufficient momentum to lift it to its highest point and falling to a different position to restore the magnet circuit while the core falls toward its previous position.
- 10 2. The combination with an oscillating momentum device, of a magnet located above said device and having its core connected to oscillate said device alternately in opposite directions when lifted by the magnet, means whereby the movement of said core after acquiring an initial momentum upwardly effects the actuation of said momentum device; means for opening the magnet circuit to permit said core to fall and the momentum device to be oscillated, and means for restoring the magnet circuit.
- 15 3. The combination with a pivoted weight, of a magnet having an upwardly movable core, means comprising a lost-motion device whereby said core acquires an initial momentum and causes said weight to be lifted and swung from one side of the pivot to the other, means for energizing the magnet to lift the core, means for deenergizing the magnet to permit the core to fall when the weight throws over, and means for re-setting the magnet circuit when the core comes to rest.
- 20 4. The combination with a movable part, of a weighted crank mounted to swing about a pivot and operating said part in opposite directions by its momentum in swinging from one side to the other, a magnet, and a link connecting the armature of the magnet and the crank, the connection permitting an initial movement of the armature independent of said weighted crank.
- 25 5. The combination with a movable part, of a weighted crank for actuating said part, a solenoid magnet, actuating connections between the core and the crank, and a pair of contacts in the magnet circuit, one of which is operated and the other closed by said movable part at each throw, and means whereby the crank moves independently of

the weighted crank during a portion of its travel.

6. The combination with a weighted movable part, of a solenoid magnet for operating it alternately between two positions, 60 means for deenergizing the magnet at each movement of said part, and for setting the circuit for the next movement of said part, and connections between the core of the magnet and said part whereby upon deenergizing the magnet, the core falls toward its initial position, and the movable part completes its movement by its own momentum.

7. The combination with a pivoted weight, 70 of a solenoid magnet located above and having its armature connected with the weight to lift and throw it from one side of the center to the other, means for opening the magnetic circuit to permit the weight to move over the center and drop by gravity, 75 and a lever connected to be moved in opposite directions according to the direction of the weight, the connections permitting the core to fall toward its initial position while the weight is moving under its own momentum.

8. The combination with a pivoted weight mounted to be thrown from one side of its pivot to the other alternately, of a solenoid located above the weight and having its 85 core mounted to throw said weight when the core is lifted, means for opening the magnet circuit to permit the core and weight to drop by gravity, and a part controlled according to the position of said weight, 90 whereby the momentum of the weight and core is available for actuating energy.

9. The combination with a magnet having a movable core, of an actuated part having a plurality of positions, a weighted device 95 having corresponding positions and adapted to operate said actuated part, means including a lost-motion device connecting said core with said weighted device, and means for automatically opening the magnet circuit to permit the core to drop while said weighted device is moving from one position to the other.

In testimony whereof I affix my signature, in presence of two witnesses.

DAVID H. DARRIN.
